UNITED STATES PATENT OFFICE.

PETER H. BRODESSER, OF MILWAUKEE, WISCONSIN.

ELEVATOR AND CARRIER.

SPECIFICATION forming part of Letters Patent No. 481,926, dated September 6, 1892.

Application filed June 15, 1891. Serial No. 396,403. (No model.)

To all whom it may concern:

Be it known that I, PETER H. BRODESSER, of Milwaukee, in the county of Milwaukee and State of Wisconsin, have invented a new 5 and useful Improvement in Elevators and Carriers, of which the following is a description, reference being had to the accompanying drawings, which are a part of this specification.

10 My invention relates to improvements in the elevator and carrier for which Letters Patent No. 451,260 were issued to me on April 28, 1891.

15 The present invention is directed to improvements in that device whereby the mechanism is simplified in some parts, is made capable of more extended use, and is provided with devices whereby its operation is facilitated and otherwise improved.

20 In the drawings, Figure 1 is an elevation of a complete device embodying my invention. Fig. 2 is a side elevation of the winding-drums and related mechanism. Fig. 3 is a top plan view of the winding-drums and related mechanism shown in Fig. 2, taken on line 33 thereof. Fig. 4 is a top plan view of the carriage and truck traveling thereon, a portion of the carriage being broken away for convenience of illustration. Fig. 5 is a vertical section of the carriage and truck on line 5 5 of Fig. 4. Fig. 6 is an elevation of a brake attached to the truck and adapted for clutching the hoisting-cable. Fig. 7 is a top plan view of the brake shown in Fig. 6. Fig. 8 is a detail of a bracket carrying the pulley, to which one extremity of the hoisting-cable is attached.

25 A is the frame on which the operative mechanism is supported and includes a two-railed track or tramway B. The outer end B' of the tramway is desirably hinged to the main part of the track, substantially as described in my former patent. A carriage C travels on the tramway and is connected to an endless cable D, which runs over pulleys E E, pivoted, respectively, at the extremities of the tramway over the pulleys F F and the thereto quartered pulleys G G and winds around the drum H. The drum H is journaled at one 30 extremity eccentrically in the cylindrical box I, revoluble in bearings therefor in the frame. The box I is provided with a fixed

lever-handle J, by which the box may be rotated sufficiently to shift the friction-wheel K, fixed on the axle of the drum H, into and 55 out of contact with friction-wheels on shafts L and N. The shafts L and N are in mechanical connection by means of a belt O, running on wheels on the two shafts, and the shaft L is provided with a band-pulley M, adapted 60 to carry the power-supplying belt. It will be understood that by shifting the drum H into frictional contact through its wheel K with the revolving shafts L or N the drum will be rotated in one or the other direction and the 65 carriage thereby run to right or left, as desired.

I provide a brake for locking the drum H, which brake consists of a strap P, looped about a wheel Q, fixed on the axle of the drum, the 70 extremities of which strap are attached eccentrically to the lever-handle R, pivoted on the frame. A spring S, interposed between the brake-handle and the frame, is advisedly used to hold the brake yieldingly out of engagement with the drum-wheel. A hoisting-cable T, attached at one end to the block of a sheave U, runs over pulleys V V', journaled in the truck W about the sheave in the load-carrying tackle-block Y and over the pulleys Z and 80 Z' and winds on the drum C'. The pulley Z is located at the outer extremity of the tramway, preferably about midway between the ways B B, and the sheave U travels laterally on a rod-bracket D', secured to the frame or a suitable 85 fixed support at the other extremity of the tramway. Opposite guide-pulleys E' E', located near to and quartered with reference to the pulley V', are journaled in the truck W and receive the hoisting-cable between them 90 and guide it over the pulley V'. The carriage C has considerable length laterally of its line of travel and the truck W travels thereon laterally, so that by reason of this lateral travel of the truck the load lifting and carrying tackle 95 Y may be shifted a considerable distance to the right or left between the rails of the tramway and at right angles to the line of travel of the carriage. The travel of the sheave U in the bracket D' is adapted to accommodate 100 the hoisting-cable to the travel of the truck W on the carriage C. As this lateral travel of the truck on the carriage is desired at the inner or right-hand end of the tramway, the

movement of the truck is permitted, so far as the pulley Z at the other extremity of the tramway is concerned, by reason of the flexibility of the cable and the distance of the carriage 5 from the pulley.

A brake for gripping the hoisting-cable consists of a cross-beam F', affixed to the truck-frame, which cross-beam is provided with an aperture G', through which the hoisting-cable 10 runs, a wedge-formed key H', movable on dove-tailed ways therefor in the cross-beam alongside of the aperture G', arranged to bear against or be released from the cable as it is pushed into or raised out of the beam, and a 15 lever I', pivoted medially on the cross-beam and connected by a pin K' to the key H'. A slot in the side of the cross-beam and a registering-slot in the lever I', into which the pin K' projects, provide for the vertical movement 20 of the key actuated by the oscillating lever. A weight L', hung on one arm of the lever I', is adapted to lift the key H' and release the hoisting-cable, and a hand-rope M', attached to the other arm of the lever, is a means for oscillating the lever and forcing the key into its seat 25 against the cable, thus gripping it to the truck. When thus gripped to the truck, the weight supported on the tackle Y tends to tighten the clutch of the key H' on the cable by reason 30 of the downward strain thereon. This brake is adapted for clutching the hoisting-cable to the truck, and thus supporting the load on the tackle Y when it has been raised to the height desired while conveying it from one 35 point to another by means of the carriage traveling on the tramway. The position of the truck upon the carriage can now also be shifted by simply manipulating rope M' laterally or by pushing the load.

40 The axle of the winding-drum C' at one end is journaled eccentrically in the cylindrical box N', revoluble in bearings therefor in the frame. The box N' is provided with a rigid lever-handle O', and thereby the friction-wheel P', fixed on the axle of the drum, may be shifted into contact with a friction-wheel 45 on the shaft L, or into engagement with a block R', fixed on the frame and serving as a brake to impede or stop the rotation of the 50 drum. By shifting the winding-drum C' into contact with the driving-shaft L the hoisting-cable is wound thereon and a load on the tackle Y is raised, and when at a sufficient height the hoisting-cable is locked to the 55 truck by means of the brake-key H', and the load is let down by releasing the brake-key and shifting the drum C' away from the driving-shaft L and holding it, if required, against the brake-block R' with such power as is necessary 60 to lower the tackle Y and its load at proper speed.

The truck W and the carriage C are each provided with flanged traveling wheels, and besides these the carriage is provided with 65 wheels S', bearing against the inside of the rails of the tramway to prevent lateral move-

ment of the carriage and undue strain on the flanges of its traveling wheels.

The truck is made to travel on the carriage C by means of lateral power being applied to 70 the hoisting-rope or the load carried thereby; or, more conveniently, the rope M', which is also employed for the purpose of operating the parts which secure the load in an elevated position, may be manipulated to accomplish 75 the same purpose and is the means which I prefer to employ therefor.

From the foregoing description of the mechanism and of the operation of the various parts thereof the use of the entire device will be 80 readily understood by all persons skilled in the art.

What I claim as new, and desire to secure by Letters Patent, is—

1. In an elevator and carrier of the class in 85 which a carriage actuated by an endless belt travels on a tramway, the combination, with the frame and two parallel shafts journaled in boxes fixed on the frame, which shafts are connected mechanically so as to revolve in 90 opposite directions, one shaft being the driving-shaft connected mechanically to the power-supply, of a drum interposed between the shafts, about which drum the endless carriage-actuating cable is wound, a friction-wheel on 95 the axle of the drum near one extremity of the drum, adapted to contact severally with corresponding wheels on the shafts, and a cylindrical box provided with a lever-handle, in 100 which box the axle of the drum at that end on which the friction-wheel is fixed is journaled eccentrically, the box itself being journaled revolvably in a bearing on the frame, substantially as described.

2. In an elevator and carrier, the combination, with a tramway and a carriage actuated thereon by an endless cable, of a truck mounted and arranged to travel laterally on the carriage, pulleys journaled in the truck at right angles to its line of motion, a hoisting-cable 105 running on and depending between the pulleys in the truck, and a sheave-block at the end of the tramway, supported and traveling laterally parallel with the truck on a rod-bracket, to which sheave-block the extremity of the 110 hoisting-cable is attached, substantially as described.

3. In an elevator and carrier, the combination, with a tramway and a carriage adapted to travel thereon, of a truck adapted to travel 115 laterally of the tramway on the carriage, pulleys in the truck, over which a hoisting-cable runs, and a sheave, to which the extremity of the hoisting-cable is attached, which sheave is supported and travels laterally parallel with 120 the truck on a bracket therefor, substantially as described.

4. In an elevator and carrier, the combination, with a hoisting-cable, of a brake for clutching and locking the cable independently of the location of the carrier on its track, comprising a suitable relatively fixed beam

through which the cable runs in an aperture therefor, a wedge-shaped key arranged to slide in ways therefor alongside the cable-aperture, an oscillating lever pivoted on the beam at 5 one side of the cable-aperture, a pin projecting from the key through a slot in the beam into an arm of the lever, a weight suspended from one arm of the lever, adapted to tilt the lever and hold the key normally out of engagement with the cable, and a hand-rope attached to the other arm of the lever, by which 10

the lever can be tilted against the action of the weight and in the other direction, whereby the key is put into engagement with the cable and the cable is locked to the beam, substantially as described. 15

In testimony whereof I affix my signature in presence of two witnesses.

PETER H. BRODESSER.
